CLAIM

The ornamental design for a game board, as shown and described.

DESCRIPTION

FIG. 1 is a top plan view of a first embodiment of my game board, showing my new design.

FIG. 2 is a top plan view of a second embodiment of my game board, showing my new design.

FIG. 3 is a top plan view of a third embodiment of my game board, showing my new design.

All embodiments of the game board are printed on a flat surface, requiring only one view, so no other views are shown.
